UNITED STATES PATENT OFFICE.

WILLIAM H. BLAKE, OF BOSTON, MASSACHUSETTS.

CONDENSER-PUMP.

1,271,841.

Specification of Letters Patent. Patented July 9, 1918.

Application filed April 19, 1916. Serial No. 92,274.

To all whom it may concern:

Be it known that I, WILLIAM H. BLAKE, a citizen of the United States, residing at Boston, in the county of Suffolk and State 5 of Massachusetts, have invented certain new and useful Improvements in Condenser-Pumps, of which the following is a specification.

This invention relates to pump condensers 10 having a by-pass through which air accumulating above the water line in the condenser, may be drawn off by the same pump that withdraws the water from and maintains vacuum in the condenser. Pump condensers as generally constructed have employed combined air and water pumps to remove the cooling water together with the water of condensation from the condenser chamber and maintain necessary vacuum 15 therein; but these are found to be quite inefficient in the development of vacuum, particularly when packings and connections become leaky and air enters the system and accumulates above the water in the vacuum 20 chamber. It has been proposed to introduce an air by-pass between the top of the water pump cylinder or cylinders, and the vacuum chamber, together with valves located to permit suction upon the by-pass 25 air pipe during the latter part of forward or suction stroke of the pump, but to close said air pipe during the downward stroke; see for instance the arrangement disclosed in U. S. Letters Patent No. 988,431, granted 30 April 4th, 1911, in the names of myself and another. But this arrangement has proven not wholly efficient in keeping down the water level, or maintaining vacuum in the condenser, besides which it is not applicable 35 to the bucket type of pump, but is limited in its application to the piston type, which pumps water at the lower end of the cylinder and air at the upper end.

One object of the present invention is to 40 provide a by-pass arrangement that will be applicable to both the piston and bucket type of condenser pumps, to which end, one feature of the invention consists in connecting the air by-pass at an intermediate point 45 of the pump cylinder, so that a portion of each water suction stroke may be utilized to draw on the air pipe.

Another object of the invention is to automatically water seal the check valve in 50 the air by-pass, and to these ends, another feature of the invention consists in combin-

ing an intermediately connected air by-pass with a bucket pump and so constructing the port and communicating passage between the valve and the pump cylinder, that at 60 each lifting stroke, the bucket will deliver a portion of the water into the valve chamber and keep it constantly flooded, though without barring a free escape of said water during a later portion of the lifting stroke, 65 when the air port is exposed to the suction created beneath the bucket.

Another object of the invention is to insure the opening of the valve in the by-pass in cases where the accumulation of air is 70 not sufficient to promptly open the air valve and keep it open the necessary length of time, as for instance when the packings are in perfect order and a comparatively small proportion of air is accumulating in the 75 condenser; and to these ends, another feature of the present invention consists in combining with an intermediately connected air by-pass, means for positively opening the valve at the proper time in the cycle 80 of movements.

Other features of the present invention relate to certain details in the construction and co-operative relationship of the parts, as will be hereinafter fully described and 85 particularly pointed out in the claims.

In the accompanying drawings—

Figure 1 shows a vertical section of a condenser and pump provided with my new by-pass;

Fig. 2 shows a back elevation of a twin condenser pump showing the relation of the new by-pass by heavy lines, and also showing means for mechanically operating same;

Fig. 3 is a vertical section of a non-divided form of the by-pass valve and its mechanical drive, and

Fig. 4 is a front view of a portion in Fig. 1, as seen in the direction of the arrow α .

Referring briefly to the parts of the known type of pump condenser which has been selected for the purpose of illustrating the application of my invention, A represents the condenser chamber and B a pump 105 of the bucket type.

Exhaust steam enters the inlet 1, while cooling water enters through the pipe 2 and passes up through the liner 3 beneath the valve 4 in a spray represented by the dotted line 5; the flow of water being controlled 110 through hand wheel 6, shaft 7, valve stem

8, and gearing 9, said gearing embodying a nut threaded on said stem and secured to the removable head 10. The upwardly sprayed water falls successively from the 5 flanges 11, 12 and 13, thus providing veils of water through which the exhaust steam must pass in entering the condenser. Water of condensation, together with the cooling water, passes downward through the neck 14 10 and into the suction base 16. Any preferred form of vacuum breaker 15 may be employed to open communication with the external atmosphere in case the water rises too high in the condenser after the engine is 15 shut down and back flow is introduced by the vacuum of the steam passages. Pipe 17 connects chamber 16 with the suction chamber 18 of the pump B. Suitably mounted upon this suction chamber with interposed 20 packing 19, are the valve seats 20 carrying the valves 21, while above these valves is the pump cylinder 22, which is preferably provided with bronze liner 23. 24 represents the pumping bucket, 25 its valves and 25 26 the discharge chamber at top of the cylinder which is provided with the usual hand-holes 27, head 28 and gland 29 for guiding and packing the pump rod 30.

I will now proceed to describe the device 30 which I combine with the known apparatus above described for accomplishing the purposes of the present invention. But in this connection, I desire it understood that the description, while referring to the 35 details of the particular embodiment of attachment selected for purposes of illustration, is not to be taken as indicating the limits of the present invention, except in so far as it sets forth certain features of co- 40 operative relationship between the parts. I also desire it understood that the attachment is applicable to apparatus embodying other forms of condenser than that selected for illustration and other forms of pump, 45 although some of its minor objects are obtainable only with the bucket form of pump, and this type is necessary to the fullest realization of all the advantages of the invention. 31 is an air check valve mounted in a 50 chamber 32 which communicates through passage 33 with the pump cylinder; the cylinder lining being provided with perforations 33^a. The casing 34 of this valve is preferably provided with a removable 55 cover 35. 36 represents the valve seat mounted within the casing. Casing 34 communicates through a pipe 37 with an opening 40 in the condenser.

The air by-pass thus established 60 communicates with the pump cylinder preferably at about two-thirds of the upward stroke of the reciprocating member of the pump (piston or bucket as the case may be), although this particular location may be 65 varied if desired. The essential feature of

this location is that it be at a point beyond which the reciprocating member travels in its suction stroke, in order that a portion of said stroke may be utilized to draw air from the condenser after exerting the necessary 70 pull upon the water in the condenser. In order to realize a still further advantage that is readily attainable with this feature of the invention, namely, the supply of sealing water to the valve from the lifting 75 bucket, it is essential that the communication of the by-pass with the pump cylinder be at a point beyond which the upper surface of the bucket passes in its downward stroke, in order that water may flow into 80 the valve chamber from the upper side of the bucket. It is to be understood, however, that while one aspect of the invention involves the use of all these characteristics in combination, the invention is not restricted 85 in its scope to the use of all of them, since each characteristic is believed to be novel in itself and to afford material advantage when present in an organization of this kind. The specific location of the port which is preferred in order to realize all of the advantages, is about two-thirds of the upward stroke of the reciprocating member. The location of the port 40 through which pipe 90 37 communicates with the condenser, is 95 largely a matter of choice, so long as it is above the water line, but it is best placed beneath the lowermost ledge or flange 13.

In operation, the air valve sealing chamber 32 will completely fill with water with 100 every upward stroke of bucket 24, thus driving out all air contained therein, so that when the bucket has passed over openings 33^a, there will be no air to expand below 105 the bucket and air-pumping action will be prompt and efficient. A small amount of water will remain on top of the bucket during the downward stroke, and there will be an opportunity for some of this water to flow into the air valve chamber 32, and 110 thus there will be a sufficient amount of water in the air valve chamber 32 to seal the air valve 31 during the short period the bucket 24 is below the opening 33 even should the air valve be partly worn and 115 freely leaking.

The chamber 32 is of such a shape and communicates with the cylinder at such position relatively to the stroke of the pump, that it forms a pocket and traps sufficient water from above the bucket on each upward stroke, to insure water-sealing of the valve 31. By having the valve 31 inverted and the pipe 37 above, accumulation of water in pipe 37 and clogging of the air 120 passages from the condenser to air cylinders is prevented. If, from one reason or another, water should collect in the pipe, it will immediately be discharged at the instant the valve opens, and thus leave a free 125 130

air passage from the condenser to the air cylinder. 38 represents an angle valve adapted to cut out the by-pass for the air, in case it should become impaired, and leave 5 the main apparatus fully operative as in ordinary pumps and condensers.

As I prefer to use a pump bucket with soft packing, the perforations 33^a will be of comparatively small diameter, so that the 10 packing will ride over them and not press out into the openings.

If the automatic valve 31 should fail to open, as for instance where there is not sufficient accumulation of air, I provide a 15 mechanical device for positively operating it. Such a positive valve-opening means is shown best in Fig. 3, where a trip-motion opens the valve as the bucket passes over the opening 33^a in the wall in the air cylinder and trips to permit the valve to close 20 at the end of the upward stroke. By the use of the mechanically operated valve, all resistance to opening will be overcome and an increase of vacuum would be obtained, 25 but in most cases, a vacuum of twenty-eight (28) inches may be produced with the automatic type of valve 31.

In adapting the device to be operated positively, air valve 31 in the casing 34, controlling the connection pipe 37, is replaced 30 by a valve 41 secured on a spindle 42 and seating against the valve seat 36 which also forms a guide for the spindle (see Fig. 3). At an intermediate point on the spindle 42, 35 is provided a water seal stuffing box 58 with a closing nut 59 and gland 60. About the middle of the stuffing box, the spindle is surrounded by an annular lantern gland 61 which has openings registering with the 40 corresponding openings in the side of the stuffing box and a pipe 62 connects these openings with the discharge chamber 26 in the pump B, so that water is always supplied to the stuffing box and forms a water seal around the spindle. The upper end of 45 the spindle 42 reaches into the dash-pot 43 and carries a dash-pot piston 44 fitting snugly therein. In this dash-pot cylinder is seated a spring 45 tending to raise the valve 50 and hold it up against its seat 36. In the bottom of the dash-pot is provided a bushing 46 for the spindle 42 and through this bushing, the guide screw 47 penetrates into the rod to prevent it from turning. The 55 lip 48, preferably made from tool steel or some other hard material, is set into the spindle 42 in a suitable position so as to be engaged by a tripping toe 49, which is also required to be made of hard material. This 60 toe is carried to slide longitudinally in a housing 50 mounted to rock on a shaft 55 which is carried in bearings in the frame 57. A small screw 51, engaging in a corresponding slot in the housing 50, prevents 65 the turning of the toe 49. The rearwardly-

extending shank of the toe 49 is surrounded by the sleeve 52 with which it has threaded engagement for the purpose of adjusting the amount of projection of the toe, and a spring 54, acting between the forward collar 70 on the sleeve 52 and a gland 53 screwed into the rocking housing 50, tends to press the sleeve with the toe 49 forward.

A rocking lever 56 connected by means of link 64 with the wrist plate 63 in the walking beam shaft, is provided to oscillate the housing 50 and the toe 49. By means of a turn buckle 65, the link 64 may be shortened or lengthened for the purpose of adjusting the opening of the air valve. It 80 will be understood that where a twin pump arrangement is employed, as suggested in Fig. 2, the valve mechanism is duplicated, and the connecting pipe 37 is branched horizontally to connect with both valve casings 85 34, as suggested in Fig. 2.

Referring particularly to Fig. 2, showing the pump operating mechanism as when the left hand bucket is in its extreme upper position, with the air valve released by the 90 tripper and forced back by spring 45 to its seat, and the right hand bucket at its extreme lower position and ready to start upward, it will be seen that the tripping toe on the right hand side has a large amount of 95 lost motion before engaging with lip 48 to open the air valve 41. The proportion between the lost motion and the acting portion of its stroke is approximately two to one, so that the lost motion of the tripping 100 toe coincides with the first two-thirds of the upward stroke of the bucket 24. Hence, the instant the bucket passes the opening 33, the air valve will be simultaneously 105 opened, making direct communication from the top of the condenser A to the vacuum cylinder 22, forming a free open passage 110 for air, without obstruction or resistance from valves. The toe 49 is timed to trip, that is, to release the air valve 31 just before the completion of the stroke of the bucket 24, so that the valve is instantly returned to its seat by spring 45, thereby allowing nothing that has been drawn into the cylinder to escape back into the condenser, the discharge instantly taking place 115 through the bucket valves on the return or downward stroke. When bucket 24 is at the lower end of its stroke, covered with a quantity of water and commencing its upward 120 movement, vacuum beneath the bucket will be practically absolute until the bucket passes over opening 33 when communication through air valve 31 with the top of the condenser A will take place and air existing in the condenser will be communicated to the air cylinder, instead of remaining 125 in the condenser until it accumulates sufficiently to force the water down and reach the air cylinder through passage 130 17.

The construction for the release of the air valve here shown is such that it may be adjusted to open from one-quarter of an inch to three-quarters of an inch; which adjustment can be made while the pump is in operation. This will permit of adjusting the air valve to open and close at a time when the best results may be obtained.

The dash pot is used to control the upward or seating stroke in the air valve and to prevent its destruction, by the very strong spring that is used in this case.

The water seal pipe 62 being connected with the discharge chamber 26, is constantly flooded while the pump is in operation, and with the water sealed stuffing box as shown in the drawing, the valve spindle is always surrounded by water and perfectly sealed.

It is customary in known pump condensers to regulate the injection cone 4 so that the amount of water used in the condenser will fill the vacuum cylinder 22 anywhere from one-half to three-quarters full at each stroke according to the amount of load carried or steam to be condensed. In the present case, the cylinder is shown two-thirds full of water, that is, up to line C—D in the drawing. In addition to steam and water entering the condenser, there is always more or less air to contend with, caused by leaking joints on stuffing boxes, etc. In machines not provided with my new device, it would evidently be impossible to exhaust air from condenser A until the water therein reaches a level denoted by line E—F, Fig. 1, a short distance below the upper wall of the pipe 17, because said pipe is water sealed and air cannot escape until the water in the condenser drops below its upper wall. Since it required nearly one pound of pressure more in the condenser, than in the cylinder, to produce this condition, there is a loss of approximately two inches of vacuum in the condenser, to sustain this difference of twenty-four inches between the water level in the cylinder and that in the condenser. This condition is to be found in all vertical bucket air pump constructions of to-day. It is the cause of making such pumps short stroke in order to avoid the forcing of water to such a high level. All these difficulties are overcome by using the appliances of the present invention, in which a communication is employed between the condenser and the air chamber of the pump above the water level, but sufficiently below the upper limit of the pumping stroke to insure an effective pull on the air during the latter portion of the pumping stroke.

60 I claim:—

1. In combination with a condenser, a vertical bucket pump having both a water-drawing connection and an air-drawing connection with the condenser; said air-drawing connection communicating with the

pump at a point between the upper and lower limits of the suction stroke of the pump-bucket; said air-drawing connection having a check valve preventing back flow from the pump, and positive means for unseating said check valve at a predetermined point after commencement of the suction stroke of the pump.

2. In combination, an exhaust steam condenser, a pump cylinder with a reciprocating bucket, a conduit between the lower ends of said condenser and said cylinder, a normally closed air connection between the condenser and the vacuum cylinder above the water level of the condenser, and a valve in said air connection, said valve having mechanical means opening it to pass air from the condenser to the vacuum cylinder during a portion of the latter half of the bucket's upstroke.

3. In combination, an exhaust steam condenser, a pump cylinder with a reciprocating suction member, a conduit between the lower ends of said condenser and said vacuum cylinder; a normally closed air connection between the condenser and the vacuum cylinder above the water level of the condenser, and a valve in said air connection, positive means whereby said valve is opened for passing air from the condenser to the vacuum cylinder during a portion of the suction member's upstroke; said valve comprising a head, a spindle for the head, a seat, a stuffing box around the spindle, and a spring to normally hold the head against said seat.

4. In combination, an exhaust steam condenser, a pump cylinder with a reciprocating suction member, a conduit between the lower ends of said condenser and said vacuum cylinder; a normally closed air connection between the condenser and the vacuum cylinder above the water level of the condenser, and a valve in said air connection, positive means whereby said valve is opened for passing air from the condenser to the vacuum cylinder during a portion of the suction member's upstroke; said valve comprising a head, a spindle for the head, a seat, a stuffing box around the spindle, and a spring to normally hold the head against said seat; said stuffing box having a water seal fed from the pump.

5. In combination, an exhaust steam condenser, a pump cylinder with a reciprocating suction member, a conduit between the lower ends of said condenser and said cylinder; a normally closed connection between the condenser and the cylinder above the water level of the condenser, a valve in said connection, and mechanical means for opening said valve to pass air from the condenser to the vacuum cylinder during a portion of the latter half of the bucket's upstroke; said valve comprising a seat, a head

- and a spindle for the head; said mechanical means comprising a lip on said spindle, a tripping toe adapted to engage said lip during a part of its stroke, an oscillating housing for said tripping toe, and a link driven by a prime mover synchronously with said pump. 65
- 5 6. In combination, an exhaust steam condenser, a pump cylinder with a reciprocating suction member, a conduit between the lower ends of said condenser and said cylinder; a normally closed connection between the condenser and the cylinder above the water level of the condenser, a valve in said connection, and mechanical means for opening said valve to pass air from the condenser to the vacuum cylinder during a portion of the latter half of the bucket's upstroke; said valve comprising a seat, a head 70 and a spindle for the head; said mechanical means comprising a lip on said spindle, a tripping toe adapted to engage said lip during a part of its stroke, an oscillating housing for said tripping toe and a link driven by a prime mover synchronously with said pump; said tripping toe being yieldingly seated in said housing. 75
- 10 7. In combination, an exhaust steam condenser, a pump cylinder with a reciprocating suction member, a conduit between the lower ends of said condenser and said cylinder; a normally closed connection between the condenser and the cylinder above the water level of the condenser, a valve in said connection, and mechanical means for opening said valve to pass air from the condenser to the vacuum cylinder during a portion of the latter half of the bucket's upstroke; said valve comprising a seat, a head 80 and a spindle for the head; said mechanical means comprising a lip on said spindle, a tripping toe adapted to engage said lip during a part of its stroke, an oscillating housing for said tripping toe, and a link driven by a prime mover synchronously with said pump; there being an adjusting member for said tripping toe to regulate its amount of protrusion, thereby timing its length of engagement with said lip. 85
- 15 8. In combination, an exhaust steam condenser, a pump cylinder with a reciprocating suction member, a conduit between the lower ends of said condenser and said cylinder; a normally closed connection between the condenser and the cylinder above the water level of the condenser, a valve in said connection, and mechanical means for opening said valve to pass air from the condenser to the vacuum cylinder during a portion of the latter half of the bucket's upstroke; said valve comprising a seat, a head 90 and a spindle for the head; said mechanical means comprising a lip on said spindle, a tripping toe adapted to engage said lip during a part of its stroke, an oscillating housing for said tripping toe, and a link driven by a prime mover synchronously with said pump. 95
- 20 9. In combination, a condenser, an exhaust pump cylinder, having a water inlet at one end communicating with the discharge end of the condenser, a single acting reciprocatory piston in the pump cylinder, and an air 100 passage affording communication between the condenser and the pump cylinder, said passage having its outlet between the limits of movement of the piston, the piston being effective during the initial suction movement 105 to draw water into the cylinder and during the latter part of its suction movement to draw air into the cylinder. 110
- 25 10. In combination, a condenser, and a single acting piston, an exhaust pump connected at one end to the condenser, a valved port connecting the pump cylinder and the condenser and positioned on the cylinder within the amplitude of movement of the piston, so that water will be drawn through 115 the cylinder during the first part of the suction stroke of the piston, and so that air will be drawn into the cylinder during the latter part of the stroke of the piston. 120
- 30 11. In combination, a condenser, an exhaust pump connected to the condenser and having a water inlet port in connection with the condenser, an air inlet port communicating with the pump cylinder and the condenser, a single acting piston whose amplitude of movement is such as to permit the piston to pass beyond the air inlet during its suction stroke to draw air into the cylinder. 125
- 35 12. In combination, a condenser, a single acting reciprocatory piston suction pump, a water passage connecting one end of the pump with one end of the condenser, a valved air passage between the condenser and the pump cylinder, the valve of which opens in the direction of the pump cylinder, the amplitude of movement of the piston in the pump cylinder being such as to cause it to pass beyond the air port opening during 130 its suction stroke to first draw water into the cylinder and then air. 135
- 40 The foregoing specification signed at Boston, Massachusetts, this 15th day of April, 1916.
